(57) CLAIM

An ornamental design for a toothbrush with an angled head, as shown and described.

DESCRIPTION

FIG. 1 is a front view of a first embodiment of a toothbrush with an angled head showing my new design;

FIG. 2 is a rear view of FIG. 1;

FIG. 3 is a right side view of FIG. 1;

FIG. 4 is a left side view of FIG. 1;

FIG. 5 is a top view of FIG. 1;

FIG. 6 is a bottom view of FIG. 1;

FIG. 7 is a front view of a second embodiment of the toothbrush with an angled head;

FIG. 8 is a rear view of FIG. 7;

FIG. 9 is a right side view of FIG. 7;

FIG. 10 is a left side view of FIG. 7;

FIG. 11 is a bottom view of FIG. 7; and,

FIG. 12 is a top view of FIG. 7.

The broken lines are for illustrative purposes only and form no part of the claimed design.
